(57) **CLAIM**

The ornamental design for a louvered vent with screen, as shown and described.

DESCRIPTION

FIG. 1 is an exploded perspective view of a louvered vent with screen showing my new design with environmental wall mount shown in broken lines and forming no part of the claimed design;

FIG. 2 is an enlarged front elevation view thereof;

FIG. 3 is an enlarged bottom plan view thereof;

FIG. 4 is an enlarged top plan view thereof;

FIG. 5 is an enlarged rear elevation view showing the four hemmed edges circumscribing the screen on the rear face of the louvered panel; and,

FIG. 6 is an enlarged right side elevation view of FIG. 5, the left side being a mirror image thereof.
